UNITED STATES PATENT OFFICE.

PAUL MARTIN ZEIDLER, OF NEW YORK, N. Y.

PIANO CONSTRUCTION.

SPECIFICATION forming part of Letters Patent No. 755,341, dated March 22, 1904.

Application filed July 10, 1903. Serial No. 164,944. (No model.)

To all whom it may concern:

Be it known that I, PAUL MARTIN ZEIDLER, a citizen of the United States, residing in the city, county, and State of New York, have invented certain new and useful Improvements in Piano Constructors, of which the following is a specification sufficient to enable others skilled in the art to which the invention appertains to make and use the same.

10 My invention is designed more particularly for use in grand and upright pianos, the object being to insure the maintenance of the original form given to the rim-case upon which the sound-board is mounted, at the same time dispensing with the wooden braces heretofore used, which have a tendency to deaden the tone of the instrument. I thus increase the resonance of the sound-board and permanently augment its volume of tone.

15 The invention consists, essentially, in a series of stay-rods the outer extremities of which are connected with or bear upon the sound-board rim and rim-brace in substantially the same plane and the inner extremities of which are connected tangentially to a centralizing-hub in two planes, one on each side of the central plane in which the said outer extremities of the stay-rods are arranged, so that the sound-board rim is practically trussed internally against the enormous strain to which it is subjected by the strings of the instrument acting through the sound-board, such strain being received and distributed uniformly over the whole rim-case by the centralizing-hub, which is free to adjust itself to all variations or inequalities of tension exerted upon and through the stay-rods.

20 My invention also includes certain other details in the construction and arrangement of parts hereinafter described and claimed specifically.

In the accompanying drawings, Figure 1 represents a plan of the under side of a sounding-board rim-case to which my invention is applied, all the non-essential parts being omitted. Fig. 2 is a section upon plane of line 2 2, Fig. 1. Fig. 3 is a section upon plane of line 3 3, Fig. 1. Fig. 4 is an elevation of one 25 end of the centralizing-hub; Fig. 5, a side

elevation of the same; Fig. 6, a transverse section upon plane of line 6 6, Fig. 5; Fig. 7, a longitudinal section upon plane of line 7 7, Fig. 4, the stay-rods being omitted. Fig. 8 is a sectional view of a portion of the sounding-board rim, showing an elevation of one of the socket-pieces embedded in the inner rim. Fig. 9 is a similar view showing the nut-bearing piece also in section. Fig. 10 is a view of the inner side of the socket-piece; Fig. 11, a view of the opposite side of said socket-piece; Fig. 12, a section taken upon plane of line 12 12, Fig. 8.

I herein show and describe simple and effective means whereby the principle of my invention is adapted in practical form to the case C of a sounding-board B, although I do not confine myself to the identical form and arrangement of parts shown, since it is obvious that various mechanical expedients may be resorted to without departing from the spirit and intent of my invention. For instance, the centralizing-hub H is preferably, though not necessarily, of cylindrical form, although a polygonal or other form might be used with like result. Various mechanical expedients other than those shown may also be resorted to in connecting the stays S S with the inner rim R, the rim-brace R², and centralizing-hub H, although one of the features of my invention is a self-adjusting bearing between the stay-rods S and the rim R and brace R² of the case C.

As shown herein by way of illustration, the cylindrical hub H is formed with a series of peripheral lugs l l, formed with holes or perforations l' l', through which the stays S S are passed. These lugs may be formed directly upon the hub H, if preferred, although I have shown them as forming part of each of the flanged caps c c, which are secured to the ends of the cylindrical hub H by pins c' c' or other suitable means. The lugs l l extend radially from the centralizing-hub H, which latter may be made of a length axially slightly less than the cross-section of the sounding-board rim R and rim-brace R², as shown in Figs. 2 and 3, so as to provide amply for the trussing of said rim, as hereinafter set forth.

The inner ends of the stay-rods S S are formed with heads or flanges $s s$, which rest and bear upon the lugs $l l$ when the stays S S are drawn taut. These heads $s s$ are preferably 5 of square or other polygonal form to adapt them for engagement with a wrench or other similar tool when necessary. The outer ends of the stay-rods S S are formed with male screw-threads $s' s'$, which engage with the female 10 screw-threads n , formed in the bearing-nut N. A portion of the bearing-nut N is formed with one or more flat surfaces n' for engagement with a wrench or similar instrument by which the nut may be rotated on its axis to 15 tighten or loosen it upon the threaded end of the stay-rod S. The bearing-nut N is also formed with a partly-spherical bearing-head n^2 for engagement with a correspondingly-formed concave bearing-surface p , formed in 20 the socket-piece P, the head n^2 and the bearing-surface p constituting, practically, a universal or ball-and-socket joint, so that the stay-rod S and bearing-nut N are free to adapt themselves axially to the direct line of tension exerted 25 when the bearing-nut is rotated upon the stay-rod S to tighten the same. Here, again, it is evident that other well known and equivalent 30 mechanical expedients may be employed for coupling the stay-rod S and the bearing-head n^2 together with like effect, the result sought and attained being a connection between the stay-rod S and the sounding-board rim R and rim-brace R^2 that will allow the parts to adapt 35 themselves automatically to perfect alignment in the shortest possible distance between the socket-piece P and the lug l upon the centralizing-hub H. The inner section R of the rim is glued to the outer section R' and to the rim-brace R^2 , so as to form an integral part there- 40 of, and this fact is of importance in the consideration of my invention, which is not designed to effect the compression of the rim-case as a whole or any part thereof, but for the sole purpose of permanently maintaining 45 the rim as a whole in its original shape—that is to say, the shape in which it was when the sounding-board was glued to it. To this end the socket-pieces P are arranged in a common plane, or substantially so, in the rim R and rim-brace R^2 , said plane coinciding approximately 50 with the middle of the inner rim R in cross-section. Alternate stay-rods S are connected with lugs on opposite ends of the centralizing-hub H, as will be understood by reference to 55 Figs. 2 and 3, so that the rim is to all intents and purposes trussed internally against change of form in proportion to the degree of tension imparted to the stay-rods, which are so distributed as to connect through the centraliz- 60 ing-hub the weakest and strongest points in the sounding-board rim-case. As a result inequality of pressure is counteracted, the same degree of strain being attained and maintained in all parts of the rim-case, thereby imparting 65 a uniform even tension to the sound-board, in-

creasing its vibratory capacity, and augmenting and imposing its quality of tone. This result is contributed to largely by the tangential arrangement of the stay-rods S with relation to the centralizing-hub H, which latter 70 is absolutely free of connection or contact with anything but the stay-rods, so that it can freely adapt itself axially as well as laterally in all directions to any torsional strain or twist to which it may be subjected during 75 the use of the instrument.

An important result of my invention is that I am enabled to dispense with the wooden braces heretofore used upon the sound-board case which tended to deaden the tone and at 80 the same time to attain a structure of greater strength and permanence, insuring an unchangeable foundation for the sound-board. My structure is thus distinguished from the prior state of the art by the abolition of 85 wooden braces upon the sound-board case and by the use of an integral rim-case trussed internally by means of a free centralizing-hub and self-adjusting tangential stays. It is not designed to compress the rim, but solely 90 to preserve and maintain its original form intact.

I am aware that tension rods or members have heretofore been known as applied to sounding-board rims and that they have been 95 connected radially to a common coupling-ring secured to the stationary and rigid framework of the piano; but such structures are not the equivalent of mine; neither do they anticipate either in result or design that which 100 I claim as my invention, namely:

1. The combination with a sounding-board and the rim-case to which it is attached, of a series of stay-rods the outer extremities of which are connected with the said rim-case, 105 and the inner extremities of which are connected with a centralizing-hub which is otherwise free and unattached, together with said centralizing-hub supported solely by said rods, and with means for adjusting the tension exerted by said stay-rods, for the purpose set forth.

2. The combination of a sounding-board, a rim-case the parts of which are united integrally and to which said sounding-board is secured, a series of stay-rods the outer extremities of which are connected with the said sounding-board rim-case, and the inner extremities of which are connected with a centralizing-hub which is otherwise free and unattached, together with said centralizing-hub supported solely by said rods, and means for adjusting the tension exerted by said stay-rods, for the purpose described.

3. The combination of a sounding-board, a rim-case the parts of which are united integrally and to which said sounding-board is attached, a series of stay-rods the outer extremities of which are connected to the said sounding-board rim-case, and the inner extremities 130

of which are connected tangentially with a centralizing-hub which is otherwise free and unattached, said centralizing-hub, and means for adjusting the tension of said stay-rods, for 5 the purpose described.

4. The combination of a sounding-board, a rim-case the parts of which are united integrally, and to which said sounding-board is attached, a series of stay-rods the outer extremities 10 of which are connected in a common plane, or substantially so, to the sounding-board rim-case, the inner extremities of said stay-rods being connected alternately in different planes to a centralizing-hub in such manner as to truss the said sounding-board rim internally, and means for adjusting the tension of said stay-rods, for the purpose 15 set forth.

5. The combination of a sounding-board rim-case, the parts of which are united integrally and to which said sounding-board is attached, a series of stay-rods the outer extremities of which are connected by universal joints with the said sounding-board rim-case, and the inner extremities of which are connected 20 tangentially with a centralizing-hub which is otherwise free and unattached, said centralizing-hub, and means for adjusting the tension of said stay-rods for the purpose set forth.

6. The combination of a sounding-board, a rim-case the parts of which are united integrally and to which said sounding-board is attached, a series of stay-rods the outer extremities 25

ties of which are connected in a common plane, or substantially so to said sounding-board rim-case by means of universal joints, the inner 35 ends of said stay-rods being connected alternately in different planes to a centralizing-hub in such manner as to truss the said sounding-board rim internally, and means for adjusting the tension of said stay-rods, for the purpose 40 set forth.

7. The combination with a sounding-board and the rim-case to which it is attached, of a centralizing-hub free and unattached, and a series of rods connected tangentially with said 45 hub and to the rim-case.

8. The combination with a sounding-board and the rim-case to which it is attached, of a centralizing-hub free and unattached, a series 50 of rods connected tangentially to said hub and to the rim-case, and a self-adjusting bearing between said rods and rim-case.

9. The combination with a sounding-board, the rim-case attached thereto, and the rim-brace, of a centralizing-hub, a series of rods 55 connected tangentially to said hub, and to the rim-case, said hub being otherwise free and unattached, and a self-adjusting bearing between said rods and rim-case and rim-brace.
